(57) **CLAIM**

The ornamental design for a power adapter as shown and described.

DESCRIPTION

FIG. 1 is a front perspective view of a power adapter showing my new design;

FIG. 2 is a rear perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged partial view of area 9, encircled in FIG. 2.

The broken lines in the Figures are for the purpose of illustrating portions of the power adapter that form no part of the claimed design.

The dash-dot broken lines are for the purpose of illustrating the boundaries of the enlargements and form no part of the claimed design.

1 Claim, 9 Drawing Sheets(56)
